CLAIM

The ornamental design for optical transceiver module, as shown and described.

DESCRIPTION

FIG. 1 is a perspective view of an optical transceiver module showing the new design;

FIG. 2 is a front view thereof;

FIG. 3 is a rear view thereof;

FIG. 4 is bottom perspective view thereof;

FIG. 5 is a side elevational view thereof;

FIG. 6 is an opposite side elevational view thereof;

FIG. 7 is a top plan view thereof; and,

FIG. 8 is a bottom view thereof.

(Continued)

The broken lines in FIGS. 2-3 and 5-6 represent portions of the optical transceiver module that form no part of the claimed design.

1 Claim, 8 Drawing Sheets
